UNITED STATES PATENT OFFICE.

JOHN E. SAUNDERS, OF EDGEWOOD BOROUGH, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY SIGNALING.

1,216,369.

Specification of Letters Patent. Patented Feb. 20, 1917.

Application filed September 12, 1914. Serial No. 361,376.

To all whom it may concern:

Be it known that I, JOHN E. SAUNDERS, a citizen of the United States, residing at Edgewood Borough, in the county of Allegheny and State of Pennsylvania, have invented certain new and useful Improvements in Railway Signaling, of which the following is a specification.

My invention relates to railway signaling. 10 I will describe certain forms of signals and of signaling systems embodying my invention and will then point out the novel features thereof in claims.

In the accompanying drawings, Figure 1 15 is a view partly in side elevation, partly sectioned and partly diagrammatic, showing one form of railway signal mechanism embodying my invention. Fig. 2 is a diagrammatic view showing a stretch of railway track having applied thereto one form 20 of signaling system embodying my invention and including signal mechanisms of the kind shown in Fig. 1. Fig. 3 is a view similar to Fig. 1, but showing a modified form 25 of signal mechanism embodying my invention. Fig. 4 is a diagrammatic view similar to Fig. 2, but including signal mechanisms of the kind shown in Fig. 3.

Similar reference characters refer to similar parts in each of the several views.

Referring first to Fig. 1, the structure here shown comprises an operating mechanism M and a semaphore 88 controlled thereby.

The mechanism M comprises a suitable 35 framework 39 in which an operating arm 42 is trunnioned at point 43. This arm is operatively connected with the semaphore 88 by a means which I will describe hereinafter. The arm 42 is operated by an electric motor 52 mounted in the framework 39 and operatively connected through gearing 54 with two chains 50 and 51. These chains are provided with rollers or studs 49 adapted 40 to engage a fork 48 carried by the arm 42 and to thereby swing the arm upwardly around its pivotal point 43. The arm 42 is arranged to occupy three distinct positions, namely, its lowest position (in which it is shown in the drawing), an intermediate position in which it is held by a stop 46 and an upper position (which I have indicated in dotted lines), in which it is held by a stop 47. The arm is moved from its lowest posi-

tion to the intermediate position by one of the rollers 49 on the chain 50, and from its intermediate position to its highest position by one of the rollers 49 on the chain 51. The fork 48 is at times held rigid with respect to the arm 42 by means of a suitable and wellknown toggle mechanism 55, which is controlled by an armature 56 of a magnet 57 mounted on the arm 42. 58 and 58^b are contacts of a circuit controller operated by the arm 42 (as indicated diagrammatically by a dotted line) for the control of the circuits of the motor 52 and of the holding magnet 57, which circuit controller operates as hereinafter explained. 59 is a circuit controller for the control of the circuit of motor 52, which circuit controller is normally closed, 65 but is adapted to be opened by a block 80 of insulation on the arm 42 when the arm reaches its highest position. As indicated in the dotted position of the arm, block 80 raises spring 60 away from spring 60^a. 53 is a buffering device for cushioning the return movements of the arm 42 and of the semaphore 88 in a usual and wellknown manner.

It will be seen from the foregoing that the arm 42 is capable of assuming three distinct positions, which, in a single mechanism of the ordinary type, correspond to the stop, caution, and clear positions of the semaphore. In the mechanism shown in Fig. 1, however, the semaphore 88 is capable of assuming two positions only, namely, the caution and clear positions; to prevent the semaphore from moving to the stop position I provide a mechanical stop, which, as here shown, comprises a clamp 84 attached to the signal post 40, which clamp carries a stud 87 adapted to engage the spectacle casting of the semaphore when the latter is in the caution position. It will be seen, therefore, that the semaphore moves only between the caution and clear positions, whereas the operating arm 42 swings through an angle corresponding to the usual movement of the semaphore from stop to clear positions. In order to permit movement of the arm 42 between stop and caution positions without causing corresponding movement of the semaphore, I connect the arm and the semaphore by a lost-motion device L, which connection I will now explain.

The lost-motion device L comprises a cy-

lindrical body member 76 having a large bore 76^a extending inwardly from one end and a smaller bore 76^b extending inwardly from the other end. Screwed into the upper end of member 76 is a rod 75, which is pivotally connected with the semaphore at point 73; this rod is held in place in the body member 76 by a lock nut 77. Screwed into the lower end of the member 76 is a nut 70, provided with a bore 70^a of the same size as the smaller bore 76^b. A rod 44 is pivotally connected to the operating arm 42 at point 73^a and extends upwardly through the bore 76^a and into the bore 76^b. Fixed to this rod inside of the member 76 is a collar 76^c, which bears against a helical spring 78 located in the large bore 76^a. The rod 44 is provided with a shoulder 73, which is adapted, when the arm 42 is raised a sufficient distance, to engage with the lower surface of nut 70 and to thereby raise the device L and the semaphore 88. The lost-motion device L is so adjusted that while the semaphore is in the caution position the arm 42 may move between its lowest position and its intermediate position without engagement of the shoulder 73 with nut 70, so that the arm then has no influence on the device L other than to compress and release the spring 78. During the movement of the arm 42 from its intermediate position to its highest position, however, the shoulder 73 engages nut 70 and raises the semaphore from its caution position to its clear position.

The mechanism shown in Fig. 1 is controlled by a relay R having a neutral armature contact 13 and a polarized armature contact 14.

The operation of the apparatus shown in Fig. 1 is as follows: I will assume first that when the parts are in the positions shown in the drawing, relay R becomes energized in such direction that its contact 13 is closed and that its contact 14—14^a remains also closed. Motor 52 is then energized through a circuit extending from battery 41, through wire 61, contact 13, contact 14—14^a, wires 72 and 66, circuit controller contact 58^a, wires 67 and 68, motor 52, wires 69 and 65 to battery 41. The holding magnet 57 is energized through a circuit which extends from battery 41, through wire 61, contact 13, contact 14—14^a, wires 72 and 62, circuit controller contact 58^b, wire 63, holding magnet 57, and wires 64 and 65 to battery 41. The magnet 57 is therefore energized to hold fork 48 rigid with arm 42 and the motor 52 is energized to move the arm from its lowest position to its intermediate position. When the latter position is reached the circuit for the motor is opened at contact 58^a, but arm 42 is held in this position by the stop 46 as long as magnet 57 continues to be energized. During this movement of the arm 42, rod 44

has been raised, but shoulder 73 has not engaged nut 70 hence the semaphore has not been moved. If now relay R is energized in such direction as to swing its polarized contact 14 to the right, the motor 52 will be energized through a circuit which extends from battery 41, through wire 61, contact 13, contact 14—14^b, wires 81 and 82, circuit controller 59, wires 74 and 68, motor 52, and wires 69 and 65 to battery 41. As soon as the arm 42 begins to move above the intermediate position, the circuit which formerly energized the holding magnet 57 will be broken at contact 58^b, but the holding magnet will then be energized through another circuit which extends from battery 41, through wire 61, contact 13, contact 14—14^b, wires 81 and 71, contact 58^b, and thence through the magnet 57 as before. As soon as the arm 42 rises above the intermediate position, shoulder 73 on rod 44 engages nut 70, and the semaphore is moved from its caution position to its clear position as hereinbefore explained.

When the semaphore is in the clear position, if the polarity of the current which energizes relay R is reversed so that contact 14 swings to the left, the circuit for magnet 57 will be opened so that fork 48 will be released, and the semaphore 88 and arm 42 then fall by gravity. Just before the caution position is reached the holding magnet 57 becomes energized by the circuit first traced for this magnet, so that the fork 48 catches on stop 46 and holds the arm 42 in its intermediate position. Then if relay R becomes deenergized it again opens the circuit of magnet 57 so that fork 48 is again released. Arm 42 then returns to its lowest position under the influence of gravity and of the spring 78.

Referring now to Fig. 2, I have here shown a stretch of railway track divided into successive sections A—B, B—C, etc. Located adjacent the entrance ends of the sections are signals S', S², S³, etc., each of which is similar to the signal shown in Fig. 1 and hereinbefore described. In Fig. 2 I have not shown all parts of the signal mechanisms, but only the semaphore 88, the lost motion device L, and the operating arm 42; the motor and circuit controllers are omitted and the circuits for the control of arm 42 are led directly to the arm in the same manner as these circuits are generally led to the semaphore arm itself in diagrammatic views of this character. Each signal is controlled, as in Fig. 1, by a relay R, which in Fig. 2 is a track relay connected with the rails of the section through which the corresponding signal governs traffic. Current is supplied to the track rails of each section by a battery 7, the polarity of the current at the rails being controlled by a pole-changer P operated by the arm 42 of

the signal next in advance. The pole-changer for each signal is so arranged that it is reversed each time the arm 42 moves from its lowest position to its intermediate 5 position or vice-versa, but is not affected by movement of the arm between its intermediate and its highest positions.

The operation of the system shown in Fig. 2 is as follows:

10 Block section C—D is occupied by a train W, consequently relay R³ is deenergized so that arm 42 for signal S³ is in its lowest position and signal S³ therefore indicates caution. Pole-changer P³ is therefore in such 15 position that polarized contact 14 of relay R² is swung to the left, so that arm 42 of signal S² occupies its intermediate position and signal S² therefore also indicates caution. Pole-changer P² is therefore in such 20 position that polarized contact 14 of relay R' is swung to the right, so that arm 42 of signal S' is in its highest position and signal S' therefore indicates clear. As the train 25 W passes out of section C—D it will deenergize relay R⁴ so that arm 42 of signal S⁴ will return to its lowest position and signal S⁴ will therefore change to caution. During 30 this movement of arm 42 of signal S⁴, pole-changer P⁴ will be reversed, so that relay R³ will be energized in such direction that arm 42 of signal S³ will change to its intermediate position, but signal S³ will continue 35 to indicate caution. During the movement of arm 42 of this signal from its lowest to its intermediate position, pole-changer P³ is reversed so that relay R² then becomes energized in such direction as to cause arm 42 of signal S² to move to its highest position, thereby causing signal S² to change 40 to clear position. During this movement of arm 42, however, pole-changer P² is not reversed, consequently relay R' and signal S' are not affected.

It will be seen from the foregoing that 45 with the arrangement of apparatus shown in Fig. 2 a train is always protected by two signals in its rear indicating "caution". The second signal in the rear of a train therefore gives a warning to the engineer 50 of a following train that he must bring his train under control prepared to pass the next signal at such speed that he can stop when he comes within sight of the train ahead. The following train is therefore not 55 required to stop at any signal, even when the signal is out of order, so that no time is wasted by unnecessary delays as is the case in the usual practice at the present day. A second train can follow a preceding train at 60 the same speed as the preceding train, so that the closest possible headway consistent with safety is secured and congestion of traffic is reduced to a minimum. The system 65 is particularly advantageous on up-grades, this being the condition most con-

ducive to congestion of traffic. It will be seen that I accomplish this control of signals without the use of line wires.

Referring now to Fig. 3, the signal here shown is the same as that shown in Fig. 1, 70 except that the semaphore 88 is adapted for the stop and clear positions only, the connection between the semaphore and the arm 42 being such that the semaphore is not moved while the arm is moving from its 75 lowest to its intermediate position, but that the semaphore is moved from stop to clear position when the arm moves from its intermediate to its highest position. That is, as 80 in Fig. 1 the movement of arm 42 from its lowest to its intermediate position merely compresses spring 78 and brings shoulder 73 into proximity to nut 70; and the movement of the arm to its highest position then raises the semaphore 88. The range of 85 movement of rod 75 is of course the same as in Fig. 1, whereas the range of movement of the semaphore in Fig. 2 is twice as great as in Fig. 1. To accomplish this I provide suitable means for multiplying the movement, which means as here shown comprises a lever 89 fulcrumed at 89^a to a fixed support 89^b. The outer end of this lever is pivotally connected at point 90 with a rod 75^a which is connected with the semaphore 88, 90 while the rod 75 is connected with the lever 89 at point 91 which is half-way between points 89^a and 90. It will be seen therefore that the range of movement of rod 75^a is substantially twice that of rod 75. The 95 operation of the signal shown in Fig. 3 will now be readily understood.

Referring now to Fig. 4, the system here shown is similar to that shown in Fig. 2, except that signals S', S², etc., are of the 105 type shown in Fig. 3. The operation of this system is as follows: Section C—D is occupied by a train W so that relay R³ is deenergized and signal S³ therefore indicates stop. Pole-changer P³ is therefore in such 110 position that polarized contact 14 of relay R² is swung to the left, so that arm 42 controlled by this relay occupies its intermediate position and signal S² therefore is in stop position. Pole-changer P² is consequently in such position that contact 14 of relay R' is swung to the right, so that arm 42 controlled thereby is in its highest position and signal S' therefore indicates 115 clear. As the train W passes out of section C—D, it will deenergize relay R⁴ so that signal S⁴ will change to stop position. Relay R³ will now become energized but pole-changer P⁴ is in such position that contact 120 14 is swung to the left so that arm 42 of signal S³ moves only to its intermediate position and signal S³ continues to indicate stop. This movement of arm 42 of signal S³ reverses pole-changer P³, thereby reversing 125 the current in relay R² so that arm 42 of signal S² 130

signal S^2 moves to its highest position and this signal then indicates clear. This movement of arm 42 of signal S^2 does not change the polarity of the current in relay R' so signal S' is not affected.

It will be seen from the foregoing that with the apparatus arranged as shown in Fig. 4, a train is always protected by two signals in its rear indicating "stop". I thus secure the advantages of a full block overlap without the use of line wires.

Although I have herein shown and described only certain forms of signals and of signaling systems embodying my invention, it is understood that various changes and modifications may be made therein within the scope of the appended claims without departing from the spirit and scope of my invention.

Having thus described my invention, what I claim is:

1. A railway signaling system comprising a plurality of successive block sections of a railway track; signals for the sections each comprising a semaphore, and an operating mechanism capable of two extreme positions and an intermediate position; means for each signal interposed between the mechanism and the semaphore for causing movement of the semaphore when the mechanism moves from its intermediate position to one extreme position but not when the mechanism moves from the other extreme position to the intermediate position, track circuits for the sections each including a source of signaling current and a track relay responsive to reversals of current for controlling the mechanism of the signal for the corresponding section, and a pole-changer for each signal operated by the signal mechanism for reversing the polarity of the signaling current in the relay for the section in the rear, each pole-changer being reversed when the mechanism moves between the last-mentioned extreme position and the intermediate position but not when the mechanism moves between the intermediate position and the other extreme position.

2. A railway signaling system comprising a plurality of successive block sections of a railway track; signals for the sections each comprising a semaphore, and an operating arm adapted for two extreme positions and an intermediate position; means for each signal interposed between the operating arm and the semaphore for causing movement of the semaphore when the arm moves from its intermediate position to one extreme position but not when the arm moves from the other extreme position to the intermediate position, track circuits for the sections each including a source of current and a track relay responsive to reversals of current, means for each signal controlled by the corresponding track relay for control-

ling the operating arm of the signal, and a pole-changer for each signal operated by the operating arm for reversing the polarity of the signaling current in the relay for the section in the rear, each pole changer being reversed when the operating arm moves between the last-mentioned extreme position and the intermediate position but not when the arm moves between the intermediate position and the other extreme position.

3. A railway signaling system comprising a plurality of successive block sections of a railway track, signals for the sections each comprising a semaphore adapted for caution and clear positions and an operating mechanism capable of two extreme positions and an intermediate position, means for each signal interposed between the mechanism and the semaphore for causing movement of the semaphore from caution to clear position when the mechanism moves from its intermediate position to one extreme position but for permitting movement of the mechanism from its other extreme position to its intermediate position independently of the semaphore; track circuits for the sections each including a source of signaling current, and a track relay responsive to reversals of current for controlling the mechanism of the signal for the corresponding section; and a pole-changer for each signal operated by the signal mechanism for reversing the polarity of the signaling current in the relay for the section in the rear, each pole-changer being reversed when the mechanism moves between its last-mentioned extreme position and its intermediate position but not when the mechanism moves between the intermediate position and the other extreme position.

4. A signaling system comprising a plurality of successive block sections, track circuits for the sections each including a source of current and a relay responsive to reversals of such current; signals for the sections controlled by said relays and each comprising a semaphore, an operating mechanism and means interposed between the semaphore and the mechanism for permitting a partial operation of the mechanism without causing movement of the semaphore but for causing movement of the semaphore during the remainder of the operation of the mechanism; and means controlled by each signal mechanism and operating to reverse the polarity of the track circuit in the rear while the mechanism is performing the first-mentioned partial operation.

5. A signaling system comprising a plurality of successive block sections, track circuits for the sections each including a source of current and a relay responsive to reversals of such current; signals for the sections controlled by said relays and each comprising

- ing a semaphore, an operating mechanism and means interposed between the semaphore and the mechanism for causing operation of the semaphore during a part only 5 of the operation of the mechanism; and means controlled by the mechanism of each signal for reversing the polarity of the track circuit in the rear during the remainder of the operation of the mechanism.
- 10 6. A signaling system comprising a plurality of successive block sections, track circuits for the sections each including a source of current and a relay responsive to reversals of such current; signals for the sections controlled by said relays and each comprising a semaphore biased toward one position, an operating mechanism, and means interposed between the semaphore and the mechanism
- 15 for permitting a partial operation of the mechanism without causing movement of the 20 semaphore but for causing movement of the semaphore to another position against its biasing force during the remainder of the operation of the mechanism; and means controlled by the mechanism of each signal 25 for reversing the polarity of the track circuit in the rear while the mechanism is performing the first-mentioned part of its operation.

In testimony whereof I affix my signature in presence of two witnesses.

JOHN E. SAUNDERS.
